UNITED STATES PATENT OFFICE

HARRY D. HORSE, OF ANDERSON, INDIANA

PRESSING MEMBER

Application filed September 29, 1930. Serial No. 485,104.

The chief object of this invention is to produce a pressing element which may be used as a head or as a buck or two elements may be utilized in which instance one will be the buck and the other the head, in a machine of the character described in the first mentioned application and so arranged that it is more satisfactory to operate than the devices herefore known and which has the further advantages of being lighter in weight, having greater strength, and being more economical to produce and to operate.

The chief feature of the invention consists in an accomplishment of the foregoing object by constructing and arranging the parts such that said objects are accomplished.

The full nature of the invention will be understood from the accompanying drawings and the description and claims as follows:

In the drawings Fig. 1 is a top plan view of a presser device, the cover plate being removed therefrom.

Fig. 2 is an enlarged sectional view taken on line 2—2 of Fig. 1 and in the direction of the arrows.

Fig. 3 is a view similar to Fig. 1 and of a modified form of the invention.

Fig. 4 is an enlarged sectional view taken on line 4—4 of Fig. 3 and in the direction of the arrows.

Fig. 5 is a top plan view of a simplified form of presser device.

Fig. 6 is an enlarged transverse section taken on line 6—6 of Fig. 5 and in the direction of the arrows.

Fig. 7 is an enlarged transverse section taken on line 7—7 of Fig. 5 and in the directions of the arrows.

In the drawings 10 indicates a pressing plate having the perforations 11 therein. Suitably secured to the perforated pressing plate is a plurality of preferably square tubes which are peripherally arranged in an outline conforming to the outline of the pressing plate, the exterior tubing being indicated by the numeral 12 and the intermediate and elongated longitudinally directed tubings being indicated by the numerals 13. Suitably secured, see Fig. 2, to the top of said tubing

by welding or the like, is a cover plate 14 and the cover plate, tubings and perforated pressing plate form steam chambers indicated by the numerals 15. Inasmuch as the steam chambers are formed in the manner before mentioned, the amount of material is considerably less than that heretofore employed in cast constructions and as a result, the amount of heat required to bring the presser device up to pressing temperature is materially less than that heretofore required. Furthermore, by reason of this construction, the weight of the several parts is considerably less than that heretofore employed so that the operator, if the presser device is employed as a head, is not unduly tired by the manual manipulation of the same. The supply lines to the heating tubes 12 and 13 are indicated by the numeral 16. The control, therefore, may be any desired, such as that disclosed in the co-pending applications referred to. Remote from the intake 16 is a take off or tap 17 having a control 18 and a discharge 19 therefrom. The control 18 includes a valve and may be suitably operated as set forth in the co-pending application entitled "Pressing machine", Serial No. 447,353, filed April 25, 1930.

The pipe 19 discharges into a header 20 and header 20 includes a discharge 21 that communicates with each of the steam chambers 15. Suitably secured adjacent the discharge port 21 is a supporting shield 22 of curved and trap formation and the same supports copper mesh screen or the like, 23. Any condensate discharged from port 21 is trapped by this mesh or screen and due to the high temperature of the latter is readily vaporized because the condensate spreads as a thin film over the surface of said screen or mesh. The automatic vent valve construction includes a housing 30 having a discharge or vent port 31 and in free communication, through the port 32, with a port or discharge 33 formed in the cover 14 of the chamber 15. A by-pass 35 discharges at 36 into the chamber 30 and the by-pass 35 communicates with the header 20. As a result thereof, the moment steam is released by valve 18 to the header 20, steam enters chamber 30 and engages

the thermo-responsive closed corrugated cylinder 38 which supports a valve member 39 for sealing the opening 31 when the cylinder is expanded. The cylinder expands or elongates because it contains a fluid which when its temperature is raised increases its volume. A diaphragm can likewise be substituted therefor, if desired. After shutting off the valve 18, the temperature in chamber 30 falls, the volume of the fluid in container 38 is reduced and valve 39 exposes opening 31 to chamber 30 so that the steam in the chamber 15 passes through the ports 32 and 33 and thence out through the port 31, venting the chamber 15.

15 In the Figs. 3 and 4 there is illustrated a modified form of the invention. In this form of the invention, similar parts are indicated by numerals of the one hundred series. The 20 chief distinction in this form of the invention is that all of the steam taken from the heating tubes of valve 117 is passed by the conduit 119 to the chamber 100 and the bottom of said chamber includes the mesh or screen 123 25 and the absorbent material 122, which receives the condensate and breaks it up into a thin film and vaporizes the same as previously set forth. The dry steam passes from chamber 100 through the port 135 into the 30 thermo-responsive cylinder construction 138. Chamber 130 includes the vent 131 closed by valve member 139 carried by the cylinder construction 138 and the same is normally closed at all times that steam is applied to the chamber 100. The header 120 includes a discharge orifice or port 132 and when the valve 139 is open, the header is vented to the atmosphere through chamber 130. When the heated steam is applied to chamber 100, said vent is 40 maintained closed.

Extending from chamber 100 is a pipe 119a which communicates with the header 120. Each header 120 includes diverging steam distributing tubes 121, which include the 45 ports or apertures 121a therein, so that dry steam supplied through line 119 from the separator 100 is discharged into the chambers 115. The steam is vented from said chambers through the ports 121, 121a, header 120, port 132, chamber 130 and vent 131.

50 In Figs. 5 to 7 inclusive, a simplified form of the present invention is illustrated. This construction reduces the weight of the presser element without affecting its efficiency. 55 This construction in addition is more efficient both as to time and cost of operation for the steaming chambers are reduced to a minimum volume without any appreciable reduction of steaming and pressing area.

60 Numerals of the two hundred series indicate like parts. The heating passages are 212 and 213, the supply and return thereto 65 216 and the steam supply for steaming 219, discharging into header 220 and thence by 70 ports 221 to each of the steaming chambers

220a and through ports 211 to the garment. This form of the invention represents a sheet metal construction.

In these figures, 210 indicates a pressing plate having the perforations 211 therein. 70 Suitably secured to the perforated pressing plate, is a plurality of preferably square tubes, some of which 212, are peripherally arranged to conform to the outline of the press tubes, some of which 212, are peripherally arranged in spaced relation. The perforated plate portion between the spaced tubes is bridged by cover plate means 214, forming steaming chambers 215. Each cover plate portion intermediate the tubes is shown as an- 75 gular.

Intermediate the ends of the presser device, there is provided a pair of end walls 200 and a cover 220-a, thereby forming separate chambers 222. Suitably mounted or secured to the cover plate 220-a, is a header 220 which communicates through the apertures 221 with each of the chambers 222 and preferably at one end thereof. The opposite end of the chamber 222 communicates through the apertures 221-a with the steam chamber 215. By the aforesaid construction, therefore, a separator arrangement is provided for each of the steaming chambers, the moisture being trapped in each chamber 222 and the steam passing through the port or apertures 221-a 80 into chamber 215 for use.

Steam is supplied to the spaced tubes 213 and the peripheral tubes 212 by the lines 216 and steam is supplied to the header 220 by the line 219. As heretofore set forth, line 219 may be connected to the line 212 in a manner similar to the manner line 19 is connected to 212 at 18, see Fig. 1, or line 119 is connected to 112 at 117, see Fig. 3.

105 The invention claimed is:-

1. In a presser device the combination of a 110 perforated pressing plate, a cover plate in spaced relation thereto, and heating tubes interposed therebetween and secured to the plates, forming chambers between the plates, a header communicating with each of said chambers, a separator associated with said header for supplying dry steam to the chambers, a vent for said chambers, means automatically opening the vent when the steam supply is cut off.

2. In a presser device the combination of a 115 perforated pressing plate, a cover plate in spaced relation thereto, heating tubes interposed therebetween and secured to the plates, forming chambers between the plates, a header communicating with each of said chambers, a separator associated with said header for supplying dry steam to the chambers, a vent for said chambers, means automatically 120 opening the vent when the steam supply is cut off, and a steam supply to said header and connected to the heating tubes.

3. In a presser device the combination of a perforated pressing plate, a cover plate in spaced relation thereto, heating tubes interposed therebetween and secured to the plates, forming chambers between the plates, a header communicating with each of said chambers, a separator associated with said header for supplying dry steam to the chambers, a vent for said chambers, means automatically opening the vent when the steam supply is cut off, and a distributing tube in each chamber and communicating with the header. 5
4. In a presser device, the combination of a perforated pressing plate, a cover plate spaced therefrom, heating tubes interposed therebetween and secured to both and forming a plurality of chambers between the tubes and with said plates, and a steam supplying header communicating with each of said 10 chambers for supplying steam thereto. 15
5. In a presser device, the combination of a perforated pressing plate, a cover plate spaced therefrom, heating tubes interposed therebetween and secured to both and forming a plurality of chambers between the tubes and with said plates, a steam supplying header communicating with each of said 20 chambers for supplying steam thereto, and a separator associated with said header for insuring a supply of dry steam. 25
6. In a presser device, the combination of a perforated pressing plate, a cover plate spaced therefrom, heating tubes interposed therebetween and secured to both and forming a plurality of chambers between the tubes and with said plates, a steam supplying header communicating with each of said 30 chambers for supplying steam thereto, a steam supply to said heating tubes and means connecting said supply to said header. 35
7. In a presser device, the combination of a perforated pressing plate, a cover plate spaced therefrom, heating tubes interposed therebetween and secured to both and forming a plurality of chambers between said 40 plates, a steam supplying header communicating with each of said chambers for supplying steam thereto, and a distributing tube in communication with said header and positioned in each chamber with which the header communicates. 45
8. In a presser device, the combination of a perforated pressing plate, a cover plate spaced therefrom, heating tubes interposed therebetween and secured to both and forming a plurality of chambers between said 50 plates, a steam supplying header communicating with each of said chambers for supplying steam thereto, a separator associated with said header for insuring the supply of dry steam, and a distributing tube in communication with said header and positioned in each chamber with which the header 55 communicates. 60
9. In a presser device, the combination of a perforated pressing plate, a cover plate spaced therefrom, heating tubes interposed therebetween and secured to both and forming a plurality of chambers between said 65 plates, a steam supplying header communicating with each of said chambers for supplying steam thereto, the steam supply to said heating tubes being connected to said header, and a distributing tube in communication with said header and positioned in each chamber with which the header 70 communicates. 75
10. In a presser device, the construction of a perforated pressing plate, heating tubes secured to said plate in spaced relation to each other, cover plate means bridging the space between the tubes and forming therewith and the perforated plate steaming chambers, and a header communicating with each of said chambers for supplying steam thereto. 80

In witness whereof, I have hereunto affixed my signature.
